BAFFLED TIME DELAY MERCURY SWITCH

James W. Campbell, Rockville Centre, N. Y.

Application September 25, 1947, Serial No. 776,128

5 Claims. (Cl. 138—42)

1

The invention relates to delay action mercury contact switches.

More particularly, this invention relates to the means for controlling the delay in the mercury flow of mercury contact switches.

The invention consists in a mercury flow control device in which the surface tension of the mercury is neutralized, that is prosophy (adhesion of the fluid) is greater than the synaphy (cohesion of the fluid) and capillary action utilized in the spaces through which the mercury passes, so as to increase the delay factor of the same quantity of mercury usually contained in the standard delay mercury switches, which type seldom attains a delay of more than seconds.

The improved device is of a material which is pre-amalgamated or "wetted" with mercury. This wetting of the surfaces enables the mercury to flow readily in a spread out form over the wetted surfaces and move by capillary action flow. As a practical embodiment, the invention contemplates a plurality or pile of copper disks, pre-amalgamated save for their circumferential surfaces, and each having a conduit passing transversely through the disk, the axis of which is substantially parallel to the axis of the disk, the conduit of one disk being staggered to the conduit of the adjacent disk. The disks, in suitable number, are held together by suitable means, in a pile, to have their radial surfaces contiguous to each other. The electrodes are also pre-amalgamated for positive make and break.

The invention will be more fully described hereinafter, an embodiment thereof shown in the drawing, and the invention will be finally pointed out in the claims.

In the accompanying drawings,

Fig. 1 is a longitudinal sectional view of the improved mercury switch including a hermetically sealed glass tube containing the improved control means, the mercury charge, and the electrodes;

Fig. 2 is a perspective view of the improved control means separate from the glass tube;

Fig. 3 is a perspective view of a single disk;

Fig. 4 is a central section of the control means;

Fig. 5 is an end view of the same;

Fig. 6 is a spaced assembly of the improved control means.

Fig. 7 is a diagrammatic drawing of a pile of disks, without shims, showing the capillary action, and

Fig. 8 shows an electrode with mercury adhering thereto.

Similar characters of reference indicate corresponding parts throughout the various views.

The improved delay mercury switch consists of a hermetically sealed glass tube 11 in which there is placed the improved control means or unit 12. An electrode connection 14 is electri-

cally connected with said unit 12 and passes out of the tube and another electrode 13 is spaced from said unit 12 and passes out of the tube.

The improved unit 12, consists of a plurality of disks 17 having an outside diameter substantially equal to the inside diameter of the glass tube 11. Each disk 17 has a central bore 23, and an off centre transverse or axially aligned conduit 19 extending from face to face of each disk 17. The disks 17 may be separated from each other by shims 18, in the form of a thin washer non-soluble by mercury, the outer diameter of which is less than that of the disks. The shims 18, when used, have a central bore 18a of substantially the same diameter as the bore 23 of the disks. The disks 17 with the intermediate shims 18, if present between the disks 17, are assembled by means of a headed bolt 16, with a washer 21, at each end of the group or pile of disks 17, and with a nut 16a engaging the threaded end 16b of the bolt 16. The disks are so disposed that the successive conduits 19 are not in alignment with each other, preferably with each conduit 19 in a successive quadrant of the next disk.

The disks 17 are made of pure copper (for practical purpose 99% purity is suitable). This has a solubility in mercury of one tenth of one percent (reference: Mellor's Chemistry). The single plates may be separately amalgamated with mercury by letting each stand in a pool of mercury for a suitable length of time. Or, each disk may be provided with a surface film of domestic solder, and then introduced into the mercury, whereby they will become immediately amalgamated. The peripheral edge 22 in each case must remain unamalgamated. This may be accomplished by staining the same with "Wright Stain," or applying an aluminium silicate and silicate of soda mixture providing the temperature when the tube is sealed is not excessive. This operates to prevent the mercury from running along the peripheral edges of the disks and between the rims of the disks and glass tube, which would short cut its intended run through the control means or unit 12. The circumferential surface of the bolt 16 is preferably covered with the foregoing stain, or the like. If the bolt is of wrought iron, this covering is not necessary. Electrolytic amalgamation may also be used.

A second set of electrodes must be placed in the lower pole of the chamber if a repeatable action is desired.

The assembled unit may be secured in the tube 55 with a tight fitting non-wettable (in mercury) sleeve, or if an aluminium silicate and silicate of soda mixture is used on the edge 22 the unit may be introduced into the glass chamber with a relatively tight fit. The tube is then sealed after a vacuum is created and is ready for service by

mounting on a known mechanical tilting device as commonly employed.

The electrodes 13 and 14 are also amalgamated with mercury, in a similar manner as for the disks, with the exception of the portion extending along the glass chamber as in Fig. 1. Electrode 14 may be secured to the proximal plate of the unit 12 if it is desirable to use the unit 12 as an electrode.

As the surfaces of the disks are wetted and are close together, they form a capillary space.

The operation of the improved switch is as follows:

On tilting the tube, the part of the mercury pool runs down to contact the first disk of the control unit 12 and enters the conduit 19, slowly oozes through the capillary space created between the disks, and then finds the conduit 19 of the second disk in its opposite lower quadrant, and continues on into the second capillary space between the next disks, and so on. At the exit end orifice of the last conduit 19 the mercury accumulates as a drop where it adheres in a rounded form of a meniscus created by the cohesion of the surface tension. As this drop gradually increases in size and weight, the weight becomes greater than the surface tension adhesion and the drop falls into the lower part of the tube 11, accumulations forming a pool of mercury. When sufficient mercury has passed from the upper pool to the lower tube to free the spaced electrode 13, then the circuit is broken.

The pre-amalgamated electrode, as copper treated with mercury, as described, is important because it being wetted, the remaining pool of mercury frees itself from the electrode abruptly, after the adhesion of the mercury to the electrode has been overcome by the weight of a cone (Fig. 8) of mercury acting through its cohesion when abrupt severance of the cone from the electrode takes place, the cone of mercury merging into the remaining pool of mercury. In the embodiment, a break action takes place. In another embodiment, where a make action takes place, the wetted or amalgamated electrode is also important, since as the pool of mercury approaches closely the electrode, a joining cone of mercury will bind the electrode and the pool of mercury, and even though the mercury pool may be vibrated as is frequently the case, the adhesion of the mercury to the electrode will be greater than the cohesion of the mercury of the pool. As adhesion and cohesion in fluids is under variables in distinction to solids, Frankenstein in 1835 prefers prosophy (adhesion of fluid) and synaphy (cohesion of fluid). This phenomena of prosophy greater than synaphy is utilized in the movement of the mercury through the contiguous surfaces of the disks, and in the use of the improved electrode surface.

The retaining of the features described depends on the selection of the material which allows this phenomenon to take place without dissolving the equipment away. We believe that copper, as pure as possible, containing little or no alloy achieves this, as its solubility in mercury is only one tenth of one percent (Mellor). Iron or platinum containing impurities may be attempted but the results will probably not be practically acceptable. Platinum obviously is too expensive. Iron actually is insoluble in mercury except for the impurities contained therein which creates a spotting and no smooth amalgamation. Other metals as gold, silver, tin, lead, in fact all the rest are quite soluble in mercury and would be dissolved out into a semi-solid amalgam or be

so eroded as to render the equipment of no further use. However, rarer metals, rhodium, molybdenum and tungsten, as also nickel and cobal, are not readily soluble in mercury, and should be considered with iron and platinum as metals which might be usable.

For finer accuracy and lack of change in the timing delay, the mercury used in the pool can be treated by placing it in contact with pure copper for a period of time so as to substantially saturate it with copper before it is introduced into the tube for sealing, which would assure the mercury of the pool when passing through the conduits and capillary surfaces from dissolving the amalgam film or the body of the disks. For most purposes this will not be necessary. It would be within the invention to install the control disks in un-amalgamated form into the tube and then operate it for a while, until the surfaces have been amalgamated, in which case the mercury would take up some copper. But, this is not practical for commercial purposes, which require testing before sale.

The more disks used in the capillary unit and the less space between plates, the greater will be the delay of the mercury flow. The tension of the bolt may be used to change the delay. The shim may be omitted for longer delays. In this case the plates would be separated by a microscopic roughness while yet affording capillary passage to the mercury. The estimated space created thusly is probably not greater than one ten thousandth of an inch, in view of the fact that a three thousandth shim gives only a four hour delay and with direct contact I have achieved 56 hours.

In Fig. 7, the capillary spaces are shown much larger than the disks, to enable action of the creeping of the mercury under capillary forces to be shown.

Mercury has a surface tension of 470 dynes per centimeter in air and a specific gravity of 13.5 in contrast to water with a surface tension of 75 dynes per centimeter in air and a specific gravity of 1. It is these two features plus the solubility of the walls or edges of the orifice or passage-way in the interposed barrier on which the mercury flow depends. I have found experimentally using a non-soluble barrier (not wetted) that a three thirty seconds of an inch circular orifice using 8 cubic centimeters of mercury in a half inch diameter tube created a five second delay with no mercury left in the upper chamber. Under similar condition, a $35/1000$ inch or about a $3/16$ of an inch orifice gave an 18 second delay with 1.3 cc. of mercury left in the upper chamber. Further, $1/64$ of an inch gave 50 seconds delay with 4 cc. left, but required about a 40 degree angle of tilt to start the flow, since at a 30 degree angle there was no mercury flow. Further, $1/100$ of an inch, gave about 55 seconds delay with $5\frac{1}{2}$ cc. left. This was at a 45-50 degree tilt, as there was no mercury flow at 30 degrees. However, with the improved device using 5 cc. of mercury and 6 disks and $11/100$ of an inch clearance with a 30 degree angle, a 3 minute delay was effected with no mercury left in the upper chamber. A $3/1000$ of an inch clearance gave a 4 hour delay with a 30 degree angle with no mercury left. An estimated $1/100$ of an inch gave 56 hours with a 30 degree angle with all mercury used.

In the case of the insoluble non-wetted or un-amalgamated orifice of the delay switches heretofore proposed, the difficulty arises in the relationship of the surface tension to the weight of the mercury. As the mercury contacts the baffle,

this non-soluble style of aperture causes the mercury to take a rounded meniscus caused by the surface tension (cohesion) which resists entrance into the orifice but will do this providing the force of the weight of mercury above it is sufficient to overcome it. This is clearly shown in the above instances, where the $1/64$ inch orifice gave 50 seconds delay but stopped with 4 cc. left in the upper chamber or exactly $1/2$ of the amount started with. It becomes apparent that as the mercury stopped, the surface tension must have just been able to exceed the force of the weight of the remaining mercury. Further, as was shown a 30 degree angle of tilt produced no flow. In this case the lessened angle of tilt reduced the head or the acting weight of the mercury above the orifice to the extent that the surface tension withholding forces were greater at the start and no flow of mercury was obtained. In contrast to this, in the improved device, an estimated $1/10,000$ of an inch space left no mercury at a 30 degree angle. This was effected because the pre-amalgamated disk broke down the surface tension forces by allowing the adhesion created by the pre-amalgamated disk to break down the rounded meniscus and convert it to a concave surface of the mercury due to the greater adhesive forces. A very positive capillary flow results which cannot fail.

While I have herein shown and described my invention in the particular form, it is obvious that structural variations may be employed without departing from the spirit of the invention, and I, therefore, do not desire to be limited to such precise forms beyond the limitations as may be imposed by the following claims.

I claim:

1. In a mercury switch, a control unit for the flow of mercury, consisting of a plurality of contiguous disks of copper, coated with a film of mercury amalgam, with narrow spaces between the disks as results from their contiguity, and each disk having a transverse conduit for guiding the mercury to a space between the disks, and for guiding the mercury from said space to the next space.

2. In a mercury switch, a control unit for the flow of mercury, consisting of a plurality of contiguous disks of copper, coated with a film of mercury amalgam, with narrow spaces between the

disks as results from their contiguity, and each disk having a transverse conduit for guiding the mercury to a space between the disks, and for guiding the mercury from said space to the next space, the circumferential rim of the disks being free from mercury amalgam.

3. In a mercury switch, a control unit for the flow of mercury, consisting of a plurality of contiguous disks of copper, coated with a film of mercury amalgam, with narrow spaces between the disks as results from their contiguity, and each disk having a transverse conduit for guiding the mercury to a space between the disks, and for guiding the mercury from said space to the next space, the circumferential rim of the disks being free from mercury amalgam and covered with a stain or a layer of a mixture of aluminium silicate and silicate of soda.

4. In a mercury switch, a control unit for the flow of mercury, consisting of a plurality of contiguous disks of copper, coated with a film of mercury amalgam, with narrow spaces between the disks as results from their contiguity, and each disk having a transverse conduit for guiding the mercury to a space between the disks, and for guiding the mercury from said space to the next space, successive conduits being disposed out of alignment with each other.

5. In a mercury switch, a control unit for the gravity flow of mercury, consisting of a member having opposed contiguous surfaces forming a narrow space as results from their contiguity, to induce a capillary action flow of the mercury, restricted means supplying mercury to said space, restricted means for discharging mercury from said space, and a coating of mercury amalgam on the surfaces over which the mercury passes.
